UNITED STATES PATENT OFFICE

153,159

DESIGN FOR A KEY CASE

Raymond P. McNeil, Stratford, Conn.

Application October 17, 1947, Serial No. 141,977

Term of patent 3½ years

(Cl. D17—14)

To all whom it may concern:

Be it known that I, Raymond P. McNeil, a citizen of the United States, residing at Stratford, county of Fairfield, State of Connecticut, have invented a new, original, and ornamental Design for Key Case, of which the following is a specification, reference being had to the accompanying drawing, forming part thereof.

Fig. 1 is a plan view of a key case, showing my new design;

Fig. 2 is an edge view thereof, and

Fig. 3 is an end view.

I claim:

The ornamental design for a key case, substantially as shown.

RAYMOND P. MCNEIL.
